UNITED STATES PATENT OFFICE.

BERTRAM E. DOWNTON, OF DEWEY, OKLAHOMA, ASSIGNOR OF ONE-HALF TO CHARLES E. SCHLAGLE, OF DEWEY, OKLAHOMA.

CHAIN FASTENER.

Application filed June 30, 1924. Serial No. 723,311.

To all whom it may concern:

Be it known that I, BERTRAM E. DOWNTON, a citizen of the United States, residing at Dewey, in the county of Washington and State of Oklahoma, have invented a new and useful Improvement in Chain Fasteners, of which the following is a specification.

This invention relates to chain fasteners. The object is to provide a device for connecting the end of chains together for various purposes, but is particularly adapted for use in connection with tire chains on automobiles, where it is essential that the fastening means may be quickly operated to permit of the ready application of the chains.

Another object is to provide a simple, strong and durable fastening means for this purpose which, having few operating parts, may be cheaply manufactured and easily assembled, the device being free of screws, bolts, or springs.

A final object is to provide a fastening for chains which will not clog up with dirt or mud to resist the operation, and which may be locked or unlocked without the use of a key or special tool, the locking means being proof against accidental separation and adapted, when applying the same to the chain, to take up the slack therein when the locking lever is swung into locking position.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a top plan view, partly in section, showing the fastener distended or open for attachment to the end link of a chain.

Figure 2 is a side elevation of the same, parts being broken away.

Figure 3 is a plan view of the device in locked position.

Figure 4 is a side elevation of the same.

Figure 5 is a longitudinal sectional view thereof.

Figure 6 is an enlarged vertical, transverse section taken on the line 6—6 of Figure 2.

Figure 7 is a detail perspective view of the locking lever.

Figure 8 is a detail perspective view of the U-shaped keeper.

Referring to the drawing there is shown a fastening device in connection with the end links of a tire chain such as are used with trucks, automobiles, and other vehicles, but I wish it understood that the invention is capable of use for general purposes where it is desired to connect the ends of chains or any two relatively movable parts or members.

The invention comprises a pair of side plates 1 and 2 respectively, which are preferably elongated and identical in shape and formed by stamping from suitable sheet metal. At one end the plates are rounded and connected together by a central rivet 3 which is adapted to be engaged by the end link 4 of a chain and to be permanently connected thereto. At the other ends the plates are provided at one side of the longitudinal center thereof with rounded lugs or projections 5 which are suitably apertured for the reception of a rivet 6, the rivets 3 and 6 being applied in a manner to rigidly hold the plates in suitable, spaced relation to each other. The parts described may be characterized as one member to be connected by the means constituting my invention.

Mounted to rotate on the rivet 6 is a locking lever 7 formed of similar metal, and having at its inner or pivoted end a rounded enlargement 8 offset to one side of said lever, and suitably apertured for the reception of said rivet 6, so that the lever may be freely swung about the same. The lever will be characterized as the movable member. At the other end the lever is curved in the same direction, as at 9, and the terminal is provided with an eye 10 which, when the lever is swung into closed or locking position, as shown in Figures 4 and 5 of the drawing, is adapted to lie at the longitudinal center line of the side plates

and adjacent to the rear rivet 3, while the outer edge of the locking lever is flush with the adjacent edges of the said side plates.

- The side plates 1 and 2 are provided with 5 a pair of spaced apertures 11 in horizontal alinement with each other and located on the center line thereof and adjacent to the rivet 3, and the said plates 1 and 2 are further provided with horizontally alined 10 apertures 12 and 13 respectively located nearer to the centers of the said plates, the aperture 12 being of the same size as the aforesaid apertures 11, while the aperture 13 is somewhat larger.
- 15 A U-shaped keeper 14, in the form of a stout staple formed of suitable non-rusting metal, is mounted in the various apertures for horizontal sliding movement transversely of the plates 1 and 2. The keeper comprises 20 a short leg 15 which traverses the apertures 11, and a longer leg 16 adapted to freely move through the alined apertures 12 and 13. The long leg of the keeper is split throughout the major portion of its length, as at 25 17, to provide spring arms capable of being contracted, and having a normal tendency to expand. The terminals of said arms are enlarged and formed into a ball-shaped head 18, the said split or bifurcation extending 30 through the same, and permitting the halves of the head to expand and contract with the arms carrying the same. The exterior diameter of the head 18, which normally lies between the plates 1 and 2, is sufficiently 35 greater than the diameter of the aperture 12 as to prevent withdrawal of the keeper therefrom, but the opposite aperture 13, being somewhat larger, will permit the ball to be forced through the same by pressure of 40 the hand of the operator to lock the keeper in its inner position, the said head being then located at the outer side of the plate 2, as shown in Figure 3 of the drawing.
- In attaching and locking the device to a 45 tire chain or other chain, or to any two members, the locking lever 7 is extended as shown in Figures 1 and 2, and the curved terminal 9 is passed through the end or outer link 19 of the chain. The curved inner face of the 50 portion 9 serves to draw up the slack in the chain as said lever is swung around on its pivot 6 to closed position. At this time the keeper 14 is in its outer position with the head 18 located between the plates 1 and 2, thus preventing further withdrawal of the 55 same, and the inner end of the short arm 15 is substantially flush with the inner face of the plate 1, as shown in Figure 1. As the locking lever is forced between the plates, the inner edge of the curved terminal 9 encounters the said head 18 and is arrested in its movement with the eye 10 in proper alinement with the apertures 11, and consequently in position for the short arm of the keeper 60 to be forced through the same and to extend 65

slightly through the other aperture 11 in the plate 2, so as to effectually prevent outward swinging movement of the lever 7. The head 18 is then at the outer side of the plate 2, and prevents any accidental sliding movement of the keeper to free the locking lever. When detaching the chains from a wheel or elsewhere, it is only necessary to pull outwardly on the keeper with sufficient force to cause the head thereof to contract sufficiently 70 to allow the same to pass through the aperture 13, when the lever will be free of the locking engagement of the short arm 15. This may be done easily by hand or, if the device is clogged by dirt or mud, a nail, stick 75 or small tool may be employed.

From the foregoing it will be seen that a simple, cheaply manufactured, and easily operated device has been provided for use in connection with tire chains or other purposes, which may be quickly applied to take up the slack therein, and by the simple swinging of the locking lever, and pressure upon the keeper, caused to permanently hold the device in locked position without danger of accidental dislodgment.

What is claimed is:—

1. In combination with two relatively movable members, one of said members having two pairs of spaced apertures, and the other member having a single aperture to aline with one of said pairs, a U-shaped keeper having a short leg movably mounted in the pair of apertures with which the single aperture is alined, and a longer leg 95 engaging with the other pair of apertures, and means whereby the longer leg may be withdrawn from one of said other pair of apertures but is held from withdrawal from the other aperture of said other pair. 100

2. In combination with two relatively movable members, one of said members having two pairs of apertures, and a U-shaped keeper in the form of a staple having a short leg and a longer leg, the latter being split 105 and provided with a ball-shaped head, said keeper having its legs movably mounted in said apertures.

3. A chain fastener comprising a pair of spaced, elongated, side plates connected together at each end, with one end permanently connected to a chain, a locking lever pivotally mounted to swing between the plate at the other end thereof and provided with a terminal eye in its free end, said plates having alined pairs of apertures arranged on the longitudinal median line thereof, and a transversely slid able keeper mounted in the apertures and adapted to have one end traverse the eye in the locking lever when the latter is closed and the staple is pushed in.

4. A tire chain fastener comprising a pair of spaced, elongated, side plates, rivets to hold the plates together at each end, one of

5 said rivets being adapted to receive the end link of a chain, a locking lever having its inner end pivotally mounted on the other rivet to be swung so as to lie between the plates, the free end of the lever being provided with an eye, said plates having horizontally alined pairs of apertures, one of said pairs being in alinement with the eye in the locking lever, and a U-shaped keeper
10 mounted to slide transversely in the pairs of apertures to permit the closing of the locking lever and then to be pushed in to cause one of the arms of the U-shaped member to traverse the eye of said lever.
15 5. A tire chain fastener comprising spaced, connected side plates attached at one end to a chain and having longitudinally alined pairs of apertures, one of the apertures of the innermost pair being smaller than the other, a U-shaped keeper mounted to slide transversely in the apertures, said keeper

having a short leg mounted in the outermost apertures and adapted to free the passage between the plates when drawn outwardly, the long leg of the keeper being split 25 and traversing the smaller inner aperture and having its terminal formed into a ball-shaped head adapted to be sprung through the larger inner aperture in the other plate in either direction, and a locking lever 30 pivoted at the other end of the plates and having its free end provided with an eye adapted to aline with the short leg of the keeper when the lever is swung to rest on the said head, and to be locked in closed 35 position when the keeper is pushed in to force the head through the larger, inner aperture.

In testimony that I claim the foregoing as my own, I have hereto affixed my signature. 40

BERTRAM E. DOWNTON.
